UNITED STATES PATENT OFFICE.

WILLIAM C. LOUD, OF DETROIT, MICHIGAN, ASSIGNOR TO GLASSMOBILE COMPANY, OF DETROIT, MICHIGAN, A CORPORATION OF MICHIGAN.

AUTOMOBILE CURTAIN.

Application filed December 1, 1924. Serial No. 753,127.

This invention relates to side curtains of automobiles wherein a glass window is mounted within a frame carried by a further supporting frame of larger size, the said frames being covered by flexible material and the inner frame suspended from or connected to the outer frame at certain points leaving one or more of its corners free from said outer frame for purposes of flexibility 10 and reduction of liability of the glass window to breakage, examples of such side curtains being described in my pending applications, Serial No. 673,236, filed Nov. 7, 1923, and Serial No. 753,125, filed December 1, 15 1924.

Without limiting the freedom of movement of the said free corners of the inner frame to an extent which would neutralize the function of such arrangement in protecting a glass window against breakage, it is in some cases desirable that certain limitations should be placed upon their movement whereby they may be prevented from penetrating or otherwise injuring the covering 20 fabric or material, particularly when they are subjected to undue influences such as when pressure is applied directly to this part of the side curtain. This occasionally occurs in the closing of vehicle doors to which such 25 a type of side curtain is applied, the person closing the door sometimes thoughtlessly exerting pressure against the side curtain adjacent the free corners of the frame instead of against the door itself.

The present invention, therefore, has as its objective the provision of a form of reinforcement which will permit the desired movement of the free corner or corners of the frame, but which will also prevent such 30 movement taking place to an extent which would be injurious to the covering fabric or material; a further object being to provide the said free corners of the frame with flexible braces or ties such as straps extending 35 to or thereover from the outer frame and to still further provide for a protective covering of such corner within the enclosing material.

A still further object is to effect the housing 40 of such a free corner in a pocket formed within the said enclosing material; and still further objects subsidiary to or resulting from the aforesaid objects, or from the construction or operation of the said invention

as it may be carried into effect, will become 55 apparent as the said invention is hereinafter further disclosed.

In carrying the said invention into effect, I may provide, in a side curtain having an outer frame and an inner frame mounted 60 therein in such manner that one or more of its corners is free of the outer frame and a fabric or other flexible covering for said frames, a strap or reinforcing strip of a flexible nature extending over each of the 65 free corners of the said inner frame within the outer covering, the said strap being sewn to the said covering to form a pocket for the said free corner and also extending to the said outer frame and secured about or 70 approximate thereto whereby the said strap has a limiting influence upon the movement of the free end of the said inner frame and forms a protective covering therefor.

All of which is more particularly described and ascertained hereinafter, by way of example, having reference to the accompanying drawing, wherein

Figure 1 is an elevation of a side curtain with part of the covering broken away to disclose the reinforcing means;

Figure 2 is a fragmentary perspective view of the lower right hand corner of the curtain shown in Figure 1;

Figure 3 is a fragmentary elevation with 85 the cover partly broken away of a modified form of the curtain, and

Figure 4 is a detail sectional view taken on the line 4^x—4^x, Figure 1.

Similar characters of reference indicate 90 similar parts in the several figures of the drawing.

The form of side curtain shown in the example comprises inner and outer frames 1 and 2 covered with layers of flexible fabric or material 3 and 4 on the back and front thereof respectively, the said inner frame being suspended from the outer frame at 5 and 6 whereby its corners 7 and 8 are free. 9 is a glass window carried within the said inner 100 frame.

The freedom of the said corners 7 and 8 acts as a protector against the breakage of the glass window but may, if permitted excessive movement, be detrimental to the 105 overlying material 3 and 4, even in some instances to an extent actually penetrating the material, and, to avoid this, I adopt means

protectively housing the said corners and also limiting or resisting the free movement thereof.

In Figures 1 and 2 these means are indicated as being in the form of diagonally disposed straps 9 which extend over the said free corners of the frame and are sewn to the fabric at 10, thereby forming pockets into which the said free corners of the inner frame extend and protectively covering the said corners so that they are prevented from abrading the fabric as may otherwise occur. The said straps have their end portions 11 extended over the outer frame 2 and secured in position by stitching 12 and 13, preventing their being pulled inwardly of the outer frame and therefore causing the said straps to resist the free movement of the corners 7 and 8 of the inner frame all though permitting sufficient movement thereof to serve the desired purposes of their freedom by reason of the flexible nature of the said straps which may be made of leather, light metal or other suitable material.

In the modified form, Figure 3, a corner strip 14 is shown, the inner end 15 of which overlaps the free end 8 of the frame and is sewn at 16 to provide a pocket therefor, the outer end 17 of the said strip overlapping the adjacent corner of the outer frame 2 and being sewn at 18 and 19. The action is very similar to that of the strips 9 as will be quite apparent without further description.

The said strips 9 in the illustrations are shown as being of doubled material, the dotted line 20 indicating the crease formed by the doubling thereof. In Figure 3 the dotted line 21 similarly indicates a crease formed by the doubling of the material forming the strip 14.

The arrangement of strips in the manner described increases the durability of a curtain of the type referred to without reducing the advantages gained by the provision of free corners on the inner frame and does not materially add to the cost of construction of the curtain, the actual amount of the material required for the said strips and time required for the application of the same to the curtain being quite small.

This invention may be developed within the scope of the following claims without

departing from the essential features of the said invention, and it is desired that the specification and drawing be read as merely illustrative and not in a limiting sense except as necessitated by the prior art.

What I claim is:—

1. In a side curtain having an outer and an inner frame, one corner of said inner frame being free from said outer frame, a covering enclosing said frames, and means protecting said covering against damage by said free corner, said means comprising a pocket within said covering into which said corner extends.
2. In a side curtain having an outer and an inner frame, a corner of said inner frame being free to move laterally within said outer frame, a covering enclosing said frames, and means protecting said covering against damage by said free corner, said means comprising a strap extending from said outer frame and enclosing said movable corner.
3. In a side curtain having an outer and an inner frame, a corner of said inner frame being laterally movable within said outer frame, a covering enclosing said frames, and means protecting said covering against damage by said free corner, said means comprising a flexible extension connecting said corner with said outer frame and covering said corner.
4. In a side curtain having an outer and an inner frame, one corner of said inner frame being free from said outer frame, a covering enclosing said frames, and means protecting said covering against damage by said free corner, said means comprising a flexible member extending from said outer frame to said corner, and having a pocket formed therein into which said corner extends.
5. In a side curtain having an outer and an inner frame, one corner of said inner frame being free from said outer frame, a covering enclosing said frames, and means protecting said covering against damage by said free corner, said means comprising a strap extending from said outer frame and overlapping said corner, said strap being sewn to said covering about said corner.

In testimony whereof I affix my signature.

WILLIAM C. LOUD.
